UNITED STATES PATENT OFFICE,

GEORGE J. TUBERGEN, OF GRAND RAPIDS, MICHIGAN.
VENDING MACHINE.

1,038,236.

specification of Letters Patent. Patented Sept. 10, 1912.
Application filed September 14, 1911. Serial No. 649,246.

To all whom it may concern:

Be it known that I, GEORGE J. TUBERGEN, a citizen of the United States, residing at Grand Rapids, in the county of Kent and State of Michigan, have invented a new and useful Vending-Machine, of which the following is a specification.

This invention relates to vending machines particularly designed for dispensing small bottles of perfume and the like, one of the objects of the invention being to provide a delivery spool adapted to be rotated so as to discharge an article when a coin of proper value is inserted into the machine and moved against the spool so as to actuate it.

Another object is to provide simple means whereby the coin, when inserted into the machine, may be forced into engagement with the spool so as to rotate it and thus discharge an article to a point where it can be reached by the customer.

Another object is to provide coin engaging and carrying means which is compact in construction, will not readily get out of order, and which will operate positively to direct a coin against the spool.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

40 In said drawings:—Figure 1 is a vertical section through a machine embodying the present improvements. Fig. 2 is a section through the lower portion of the machine and showing the positions of the parts while 45 the spool is being engaged by an inserted coin. Fig. 3 is a front elevation of the lower portion of the machine with the front panel removed, the return chutes being shown in section. Fig. 4 is a section on line 50 A—B Fig. 1. Fig. 5 is a perspective view of the coin chute and the return chute. Fig. 6 is a perspective view of a portion of the sectional shaft used for rotating the coin wheel. Fig. 7 is a perspective view of the 55 coin wheel. Fig. 8 is a perspective view of a modified form of coin wheel. Fig. 9 is a

horizontal section through a portion of a modified form of machine.

Referring to the figures by characters of reference 1 designates a casing having upper and lower panels 2 and 3 respectively mounted in the front thereof, said upper panel being formed with a transparent portion through which the articles to be sold may be viewed and the panel 3 having a delivery opening 4 near the bottom thereof and one or more coin receiving slots 5 near its top. A guide plate 6 extends upwardly and rearwardly from the lower portion of the panel 3 and has one or more slots 7 in the upper portion thereof for the reception of the coin chute or chutes hereinafter described. This plate 6 cooperates with the panel 3 to form a pocket 8 into which the articles to be sold are dropped in the manner hereinafter set forth and thus guided to the opening 4 where they can be reached by the customer. A mirror, such as shown at 9 may be secured on the plate 6 directly back of the opening 4.

In the type of machine shown in Figs. 1 to 4 inclusive two slots 5 are to be used and one coin chute extends from each of the slots. As shown in Fig. 5 each coin chute consists of spaced plates 10 having laterally extending flanges 11 secured in any suitable manner to a cross rail 12 within the casing 1. A flat tube 13 extends from the plates 10 to the slots 5 and has one side cut away so as to form a coin supporting ledge 14 and a coin retaining flange 15, said flange being arranged along the upper portion of the tube while the ledge 14 is located at the bottom thereof. The distance between the ledge and the flange is slightly less than the diameter of a coin of the proper denomination. The plates 10 and tube 13 are preferably slightly inclined so that when a coin which is smaller than the one to be used for operating the machine, is inserted into the tube 13, it will tilt laterally through the open side of the tube and under the retaining flange 15. A coin of the proper size, however, will roll along the ledge 14 and be prevented from tilting laterally by the flange 15. Tube 13 extends through one of the slots 7 and the open side of the tube is arranged within the upper portion of the pocket 8 so that the discharged coin will fall into the pocket and be delivered to the user through the opening 4. If preferred, however, an inclined guide chute 16 may be ex-

2
tended under tube 13 and along the open side thereof so that a coin of insufficient value, when discharged through the open side of the tube, will fall onto the chute 16 and slide therealong and be discharged into the casing 1 and back of plate 6.

Parallel vertical guide cleats 17 are arranged within the upper portion of the casing, these cleats being disposed in pairs and 10 one pair being provided for each coin chute. The cleats are adapted to hold between them a vertical column of small bottles, such as indicated at C, the end portions of the bottles slidably engaging the cleats so that said 15 bottles can move downwardly by gravity. Each column of bottles is supported by a spool 18 journaled within the casing 1 above the cross strip 12 and having a series of longitudinally extending peripheral recesses 19 20 one of which constantly registers with the lower ends of the cleats so as to permit the lower bottle of the column to rest within the groove. A spring strip 20 is secured to strip 12 and bears upon each spool 18, said 25 spring serving to retard the rotation of the spool and to always keep one of the recesses directly under the column so as to receive one of the bottles. The upper portion of the plate 6 extends close to the lower portion 30 of the spools and a guide plate 21 extends from the cleats 17 and downwardly and forwardly concentric with the spools so as to prevent the bottles from dropping out of the recesses 19 until after they have 35 passed the lower end of the plate 21 whereupon they are free to fall directly into the pocket 8.

A shaft 22 is journaled in the plates 10 and is preferably made up of sections, as 40 shown in Fig. 6, each section having a tongue 33 adapted to project into a corresponding notch 34 formed in the next adjoining section. A crank 35 is connected to one of the end sections of the shaft and is 45 arranged outside of the casing, whereby said shaft can be readily rotated by the operator. A ratchet wheel 36 is secured to one of the shaft sections and is normally engaged by a pawl 37 whereby rotation of the shaft in 50 one direction is prevented.

One shaft section is preferably arranged under each spool 18 and each of said shaft sections has a coin wheel 38 secured to it and mounted for rotation between the plates 55 10. Each coin wheel has a plurality of coin receiving recesses 39 in its periphery, each recess being slightly less than semi-circular and the wall of the recess merging into a convex edge extending to the outer end of 60 the wall of the next adjoining recess. In other words the marginal portion of the wheel is made up of a series of ogee curves the concave portions of which are sufficiently large to receive portions of coins of 65 proper sizes. As shown in Fig. 7 the coin

wheel can be formed with four coin receiving recesses or, if preferred, and as shown in Fig. 8, said wheel can be formed with two oppositely disposed coin receiving recesses. It is to be understood that under 70 ordinary conditions the shaft 32 can be readily rotated because the spools 18 are supported above the wheels 38 and will not prevent their rotation. When, however, a coin of proper value is inserted into one of 75 the slots 5, it will roll along the tube 13, being retained therein by the flange 15, and will finally drop into the coin receiving recess 39 in wheel 38. By then rotating the shaft 32 by means of crank 35, the coin will 80 be elevated by the wheel so as to move upwardly and thence rearwardly against the spool above the coin and thus cause the spool to rotate, carrying with it one of the bottles engaging the spool. Said bottle will 85 be discharged from under the plate 21 and will drop into pocket 8 from which it can be removed by reaching through the opening 4.

As hereinbefore stated, should a coin of 90 improper value be inserted in the machine, it will tilt out of the cut away portion of the tube 13 and either fall into the pocket 8 and thus be returned to user or else be carried by the chute 16 to the space back of 95 plate 6 where it will be kept with the other coin deposited in the machine. It is to be understood of course that any desired number of spools may be employed, one spool being used in connection with each column 100 of bottles. It is only necessary that a wheel be provided for each spool and that a coin chute be employed for directing a coin to any one of said wheels. By utilizing a sectional shaft 32, one or more sections can be 105 added or removed so as to adapt the shaft to machines of any size.

As shown in Fig. 5, the plates 10 may be formed with openings 40 through which the proper coins may be discharged should they, by any chance, fail to tilt laterally out of the cut away portion of tube 13.

Instead of mounting the spools 18 along a straight line under a straight series of columns of bottles, said spools can be journaled within a rotary frame, such as indicated at 41 in Fig. 9, any suitable means being provided whereby the frame can be turned so as to bring any one of the spools and the column of bottles thereabove, into 115 position above the coin wheel. With this structure only one coin wheel and chute is necessary in order to operate the various spools.

What is claimed is:—

1. In a vending machine, a revoluble element having recesses for the reception of articles to be dispensed, a revoluble coin receiving member, and means for actuating said member to shift a coin into and out of 120 125 130

one of said recesses, subsequent to the discharge of an article from the recess, to rotate said element.

2. In a vending machine, a revolute element having recesses each shiftable successively to receive an article to be dispensed, to deliver said article, and to receive an actuating coin, a revolute coin receiving member, and means for actuating said member to move the coin into one of said recesses and actuate the revolute element.

3. A vending machine including a revolute dispensing element having article receiving portions, a coin wheel revolute independently of said element and having a peripheral coin receiving recess, means for directing a coin into the recess, means for rotating the wheel to move the coin against said article receiving portions, and to actuate the dispensing element, and means close to the sides of the wheel for holding the coin in engagement with said wheel during the actuation of the dispensing element.

4. A vending machine including a revolute dispensing element having article re-

ceiving portions, a coin wheel having a peripheral recess, means for directing a coin into the recess, and means for rotating the wheel to direct the coin against said article receiving portions and to actuate the dispensing element.

5. In a vending machine the combination with spaced separately revolute dispensing elements, having article receiving grooves, of a sectional shaft, a coin wheel secured to 35 each section of the shaft and having a coin receiving peripheral recess, said shaft sections being revolute together, and means for rotating the shaft to simultaneously actuate the wheels, the coin carrying wheel 40 constituting means for directing a coin into one of the grooves to actuate the element adjacent thereto.

In testimony that I claim the foregoing as my own, I have hereto affixed my signature in the presence of two witnesses.

GEORGE J. TUBERGEN.
